UNITED STATES PATENT OFFICE.

WILLIAM J. PARSONS, OF MONTAGUE, MASSACHUSETTS, ASSIGNOR TO MILLERS FALLS COMPANY, OF MILLERS FALLS, MASSACHUSETTS, A CORPORATION OF MASSACHUSETTS.

TELESCOPIC WRENCH.

1,417,683.

Specification of Letters Patent. Patented May 30, 1922.

Application filed December 8, 1921. Serial No. 520,894.

To all whom it may concern:

Be it known that I, WILLIAM J. PARSONS, a citizen of the United States, residing at Montague, in the county of Franklin and 5 State of Massachusetts, have invented new and useful Improvements in Telescopic Wrenches, of which the following is a specification.

This invention has for its chief object to 10 provide a wrench whereby a jack-screw located more or less inaccessibly under a motor vehicle, may be operated by a person standing beside the vehicle, and to provide a strong, simple and durable wrench structure 15 adapted to be folded in compact form for storage in a tool-box, and to be quickly and conveniently extended and adapted for use.

Of the accompanying drawings forming a part of this specification,—

20 Figure 1 is a side elevation, showing a wrench embodying my invention engaged with a member of a jack-screw, a portion of the wrench being broken away.

Figure 1^a is a side elevation of the portion not shown by Figure 1.

25 Figure 2 is a side view showing the wrench folded.

Figure 3 shows the wrench on a larger scale, and a portion of a jack-screw, the inner 30 member of the wrench and a portion of the outer member being shown in section.

Figure 4 is a section on line 4—4 of Figure 3.

Figure 5 is a section on line 5—5 of Figure 3.

Figure 6 is a section on line 6—6 of Figure 3.

The same reference characters indicate the same parts in all of the figures.

40 The wrench includes an elongated tubular inner member 12, having a polygonal wrench socket 13, at one end, preferably of hexagonal form, and adapted to receive and rotate a hexagonal member 14, projecting from 45 a jackscrew, the member 14 being an element of mechanism which raises and lowers the screw-threaded member 15 of the jack-screw when the member 14 is rotated in a bearing 16. The socket 13 is formed in an

50 inner collar or sleeve 13^a, which is internally threaded and screwed on to the inner end of the member 12, the latter being preferably a length of tubing. The outer end of the member 12 has a polygonal bore portion 17, preferably hexagonal, and formed in an outer

collar or sleeve 17^a, which is internally threaded and screwed onto the member 12, the bore portion 17 being a somewhat reduced extension of the bore of said member. Each of the sleeves 13^a and 17^a has an enlarged bore portion receiving an end of the tube 12, and a polygonal bore portion of smaller diameter, projecting from the tube, as shown by Figure 3.

The wrench also includes an elongated 60 outer member 19, composed of a solid rod of polygonal and preferably hexagonal cross section, having a sliding fit in the bore portion 17, and thus slidably engaged with the inner member 12, to longitudinally extend 65 and contract the wrench. The outer member 19 is adapted by its polygonal form, and by the polygonal form of the bore portion 17, to rotate the inner member. The outer

member 19 being solid, and having a complete zone of its polygonal perimeter in contact with the polygonal bore portion 17, it follows that a strong, durable, and simple

connection is provided whereby the outer member is adapted to rotate the inner mem- 70 ber, without liability of breaking either of the members of the connection.

75 The wrench is adapted for use by extending it longitudinally to the limit permitted by a stop enlargement 19^a formed on one 80 end of the member 19, and abutting against the inner end of the bore portion 17. The outer member 19 is adapted by its polygonal form, and by the polygonal form of the bore portion 17, to rotate the inner member. The outer

member 19 being solid, and having a complete zone of its polygonal perimeter in contact with the polygonal bore portion 17, it follows that a strong, durable, and simple

connection is provided whereby the outer member is adapted to rotate the inner mem- 70 ber, without liability of breaking either of the members of the connection.

The wrench is adapted for use by extending it longitudinally to the limit permitted by a stop enlargement 19^a formed on one 85 end of the member 19, and abutting against the inner end of the bore portion 17. The wrench when applied to the jack member 14, is interlocked with said member, and its members 12 and 19 are at the same time 90

interlocked with each other to prevent accidental longitudinal contraction of the wrench, by two spring-pressed detents 21 and 22, at opposite end portions of the wrench member 12. The detent 21 is adapt- 95

ed normally to engage an annular shoulder 23, formed by one edge of a peripheral groove in the jack member 14. The detent 22 is adapted normally to engage a shoulder 24 formed by one end of a recess in the outer 100

wrench member 19. Said detents are manually displaceable, and each includes a longer and a shorter arm and a connecting neck, the shorter arm constituting the acting por- 105

tion of the detent, as shown by Figures 4 and 5. The longer arm of the detent 21 slides in a guide 25, in one side of the center of the sleeve 13^a, and projects from said

guide so that it may receive displacing pressure from the operator's finger. The longer 110

arm of the detent 22 slides in a guide 26, in one side of the sleeve 17^a, and is also adapted to receive displacing pressure from a finger. Each detent is controlled by a spring 27.

5 The stop enlargement 19^a is freely movable in the tube 12, and is adapted to enter the inner end of the tube before the inner sleeve 18^a is applied. When the inner sleeve is applied, the stop enlargement is confined 10 against withdrawal from either end of the inner member formed by the tube 12 and the sleeves 13^a and 17^a. Provision is therefore made for conveniently assembling the inner and outer members, and limiting the movement of the outer member in each direction.

The outer end of the outer member 19 is provided with a transverse socket 28, preferably formed in a sleeve or collar 29, attached, as by a pin 30, to the member 19. 20 31 represents a handle-bar adapted to slide endwise in said socket, and occupy an operative position presenting two grip portions projecting from opposite sides of the member 19, as shown by Figures 1^a and 25 3, and to be moved to an inoperative position at one side of the member 19. The handle-bar is provided with means permitting it to be folded beside the wrench, as shown by Figure 2, without being 30 disconnected from the member 19. To this end I preferably provide one end of the handle-bar with a reduced and curved extension 32, adapted to slide loosely in the socket 28, and permit the described folding 35 of the bar. The extension is provided with a stop enlargement 33, adapted to abut against one side of the collar 29, and prevent the withdrawal of the extension from the socket 28.

40 The handle-bar 31 is provided centrally with a peripheral groove having a bevelled end 34 and a flat end 35. In a socket in the outer wrench member 19 is a detent 36, which is pressed by a spring 37 into said groove, and 45 normally confines the handle-bar in its operative position. The bevelled end 34 causes the detent to yield when the handle-bar is forced endwise toward its inoperative position. The flat end 35 is so formed that the 50 bar cannot be moved endwise in the opposite direction. The handle-bar is therefore adapted to be conveniently disengaged from the detent, and displaced in one direction and folded, and is not displaceable in the 55 opposite direction from its operative position.

I claim:

1. A telescopic wrench comprising an elongated inner member composed of a tube, 60 and an inner and an outer sleeve, each sleeve having an enlarged bore portion receiving an end of the tube, and a polygonal bore portion of smaller diameter projecting from the sleeve, the polygonal bore portion of the 65 inner sleeve constituting a wrench socket,

and the polygonal bore portion of the outer sleeve constituting a coupling part and a guide; and an outer member composed of a solid rod polygonal in cross section, and slidably engaged with the bore of the outer 70 sleeve to longitudinally extend and contract the wrench, the outer member being provided at its inner end with a stop enlargement, movable freely in the tube portion of the inner member, and adapted to abut against 75 a shoulder on the said outer sleeve, to limit the elongation of the wrench, said stop enlargement being insertible in the tube portion of the inner member before the application of the inner sleeve, and prevented from 80 withdrawal from said tube portion when the inner sleeve is applied.

2. A telescopic wrench substantially as specified by claim 1, the sleeves of the said inner member being provided with spring- 85 pressed detents, one adapted normally to engage a part engaged by the said wrench socket, and the other to engage the outer member when the wrench is extended, so that, when the wrench is in use, its socket is 90 interlocked with said part, and the outer member is interlocked with the inner member, each of said detents including a longer and a shorter arm, and a connecting neck, the shorter arm constituting the acting portion of the detent, and the longer arm being movable in a guide at one side of the longitudinal center of the sleeve by which it is carried, and projecting from said sleeve to receive displacing pressure, the arrangement being such that inward pressure on the projecting portion of the longer arm 95 outwardly displaces the shorter arm.

3. A telescopic wrench comprising an inner member having a wrench socket; and an outer member slidably engaged with the inner member, to longitudinally extend and contract the wrench, said members being interengaged to cause rotation of the inner member by the outer member, the outer 105 member being provided with a transverse socket in its outer end portion; and a handle-bar slidable endwise in said socket to an operative position presenting hand-grip 110 portions projecting in opposite directions from the outer member, and to an inoperative position wholly at one side of the outer member, one end of the handle-bar being provided with means permitting the folding 115 of the bar beside the wrench when the bar 120 is moved to its inoperative position.

4. A telescopic wrench comprising an inner member having a wrench socket; and an outer member slidably engaged with the inner member, to longitudinally extend and 125 contract the wrench, said members being interengaged to cause rotation of the inner member by the outer member, the outer member being provided with a transverse socket in its outer end portion; and a han- 130

dle-bar slidable endwise in said socket to an operative position presenting hand-grip portions projecting in opposite directions from the outer member, and to an inoperative position wholly at one side of the outer member, one end of the handle-bar being provided with a reduced curved extension formed to slide loosely in said socket and permit the folding of the bar beside the wrench, said extension having a stop enlargement preventing the withdrawal of the extension from the socket.

5. A telescopic wrench comprising an inner member having a wrench socket; and an outer member slidably engaged with the inner member, to longitudinally extend and contract the wrench, said members being interengaged to cause rotation of the inner member by the outer member, the outer 10 member being provided with a transverse socket in its outer end portion; a handle-

bar slidable endwise in said socket to an operative position presenting hand-grip portions projecting in opposite directions from the outer member, and to an inoperative position wholly at one side of the outer member, one end of the handle-bar being provided with means permitting the folding of the bar beside the wrench when the bar is moved to its inoperative position, the said 15 handle-bar being provided centrally with a peripheral groove, one end of which is bevelled; and a spring-pressed detent normally projecting into said socket and formed to engage the ends of said groove and confine the handle-bar in its operative position, said detent being displaced by the said bevelled end when the bar is moved toward its inoperative position.

10 In testimony whereof I have affixed my signature.

WILLIAM J. PARSONS.
